COMBINATION BRACELET AND COSMETIC HOLDER

Jules I. Hackel, New York, N. Y.

Application August 11, 1934, Serial No. 739,421

4 Claims. (Cl. 132—82)

This invention relates to combined bracelets and cosmetic holders and has for one of its objects the provision of such a device comprising a sheet metal frame bent up or ribbed at one portion thereof to form compartments for supporting cosmetic boxes or cases, the remainder of said frame being covered with a layer of any suitable material such as for instance hard rubber, bakelite, bone, ivory, pyroxylin, etc.

Another object of the invention is to produce such an article which will present an even exterior, and will not be encumbered with hideous bulges or extensions.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawing, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawing, in which Figure 1 is an end view of my improved bracelet and cosmetic holder; Figure 2 is a top plan view thereof with a portion of one of the cosmetic holders broken away; Figure 3 is a fragmental sectional view taken on line 3—3, Figure 1; Figure 4 is a fragmental perspective view of the metal frame; Figure 5 is a fragmental sectional view of a modified form of the invention; and Figure 6 is a top plan view thereof.

Referring now to the drawing in detail, 10 indicates a band preferably made of thin sheet metal bent to fit the wrist and provided with bent up walls or ribs 11 which divide the upper portion of the frame into compartments 12, 13 and 14. The compartments 13 and 15 are made large enough for the reception of the usual or standard size rouge or powder compact or boxes 16, while 55 the central compartment 14 is large enough for

the reception of a lipstick holder 17. The outer surface of the frame 10, between the outermost ribs 11, is covered by a covering, or filling layer or segment, 18, made of any suitable material such as for instance bakelite, hard rubber, etc., 60 of any desired color, the cosmetic receptacles being colored similar to the color of the said non-metallic segment or cover 18.

The powder and rouge boxes 16 as well as the outer casing 20 of the lipstick holder 17 may be 65 either riveted, brazed or soldered to the band 10 or they may be otherwise held in their respective compartments as for instance by friction.

It will be seen by referring to the Figures 1 to 3 of the drawing that access may be had to the 70 interior of the rouge and powder boxes 16 by merely swinging the lids or covers 21 upwardly and the lipstick 22 may be withdrawn from its casing 20 by pulling same upwardly as shown in Figure 2.

In Figures 5 and 6 I have shown a modified form of the invention wherein instead of bending the band 10 upwardly to provide the compartments I depress the said band to form a sunken compartment 25. While I have shown this modification as comprising but a single such compartment it is to be understood that a plurality of such compartments may be provided if desired.

In this embodiment of my invention I have shown the lipstick holder casing 20a as pivoted 85 at 26 upon which pivot it may be swung upwardly by the insertion of a finger nail under the extension 27 provided for this purpose to withdraw the lipstick. A detent 28 maintains the lipstick receptacle in normal lowered position. Inasmuch 90 as the compartment 25 is depressed, a non-metallic lining 29 is provided at the inside of the band 10. If desirable a thin outer covering 18a may also be provided.

From the foregoing it will be seen that I have 95 provided a simple inexpensive and yet attractive and efficient combined bracelet and cosmetic holder.

Having described my invention what I claim 100 as new and desire to secure by Letters Patent is:

1. A combined bracelet and cosmetic holder, comprising a frame, spaced apart walls bent from said frame to form a compartment therebetween, a receptacle secured in the said compartment, and a segment of suitable material on the said 105 frame extending between the outer surfaces of the walls.

2. A combined bracelet and cosmetic holder, comprising a frame, spaced apart walls bent from said frame to form a plurality of compartments, 110

- a receptacle in each of the compartments, and a filling layer extending around the frame between the extreme outer walls thereon.
3. A combined bracelet and cosmetic holder, comprising a substantially thin sheet metal band, upstanding spaced apart walls bent from the said metal band to form a compartment therebetween, a receptacle in the said compartment, and a non-metallic filling segment secured to the frame and extending between the outer surfaces of the said walls.
4. A combined bracelet and cosmetic holder, comprising a substantially thin sheet metal band, a pair of spaced apart walls bent downwardly from the said band to form a compartment, a cosmetic receptacle pivotally mounted in the said compartment and a non-metallic filling segment secured to the band and extending between the outer surfaces of the said walls. 80
